ABSTRACT

A method and apparatus for producing selected visible characters on successive portions of a recording area in which a contoured beam of radiation of an outline corresponding to the respective selected character is projected at a layer of particles maintained over the recording area so as to change the physical and/or the chemical properties of the irradiated particles and to form from the irradiated particles a visible image according to the selected character on the recording area.

**METHOD AND DEVICE FOR PRODUCING PRINTS
AND THE LIKE**

**CROSS-REFERENCE TO RELATED
APPLICATIONS**

This is a continuation of application Ser. No. 59,134 filed on July 29, 1970, now abandoned, which in turn is a continuation-in-part application of the copending application Ser. No. 405,330 filed on Oct. 13, 1964 for "Method and Device for Producing Prints or the Like" now abandoned.

BACKGROUND OF THE INVENTION The present invention relates to a method and apparatus for producing selected visible characters on a recording area by irradiating particles located in the region of the recording area with a contoured beam of radiation of an outline corresponding to the respective character to thereby produce from the radiated particles a visible image according to the selected character on the recording area.

Most of the methods used to produce visible characters such as print on a recording area used printing types which are arranged on key levers, rollers or the like which are applied by mechanical or electromechanical means against the recording area with a color carrier such as ink, an inked ribbon or the like interposed between the printing types and the recording area.

These known typing and printing means have, however, various disadvantages.

First of all, the making of conventional typewriters requires a substantial amount of mechanical high precision components whose proper assembly and adjustment is expensive and requires high-skilled labor.

Furthermore, typewriters and similar printing apparatus have a large number of relatively heavy components which, for reason of stresses they are subjected to during operation, cannot be made from lighter and cheaper synthetic material, and the mass forces encountered during operation of such apparatus do not permit to increase the typing or printing speed substantially beyond 15 strokes per second. This is of special disadvantage in typewriters or similar printers which are constructed for automatic operation from memories or storages such as for instance perforated tape.

Another disadvantage of such apparatus is the relative loud noise they produce during operation which, even by use of sound absorbing means, cannot be reduced to a desired minimum.

Besides the above mentioned prior art printing and typing devices, other systems for producing visible characters are known which, although they include types, do not require a mechanical stroke. Such devices include for instance magnetic typing systems wherein the types are magnetically conductive and, as an exciter magnet is turned on, will produce a change of the magnetized condition on a magnetic carrier corresponding to the respective character to be printed. In such systems, however, there will be produced first an invisible magnetized image on an intermediate carrier, which only subsequently by powdering this magnetized image by means of a magnetic powder will produce a visible image on the actual recording surface, and such visible image has to be fixed substantially to the recording surface by heat.

Such systems which require, besides the actual printing operation, transfer and fixing operations are expensive and time-consuming in addition do not permit direct reading of the character produced on the recording area during the actual typing operation.

Other systems are also known in which the print or type character is first projected by optical means on an intermediate carrier and fixed thereto by an electric charge. The thus-produced character is however still invisible and will become visible on the recording area only after the completion of several additional method steps.

Such systems have therefore also the disadvantage that the characters thus produced cannot be read during the actual typing or printing operation and that they require expensive auxiliary devices for charging, powdering and cleaning of the intermediate carrier and the transfer of the intermediate invisible image to the record carrier on which it is finally fixed in form of a visible image.

SUMMARY OF THE INVENTION

It is an object of the present invention to provide a method and apparatus for producing selected visible characters on successive portions of a recording area and which avoid the disadvantages of methods and apparatus known in the art for this purpose.

It is a further object of the present invention to provide for a method and apparatus of the aforementioned kind which can be operated at a speed far exceeding the speeds of typing and similar printing apparatus known in the art.

It is also an object of the present invention to provide for a method and apparatus of the aforementioned kind which will produce visible characters during the actual printing operation.

It is an additional object of the present invention to provide for an apparatus of the aforementioned kind which is relatively simple in construction so as to be producible at reasonable cost and so as to operate trouble-free under extensive use.

With these objects in view, the method according to the present invention of producing selected visible characters on successive portions of at least one recording area mainly comprises the steps of positioning a selected one of a plurality of character forming means adjacent a selected portion of the recording area, influencing a beam of electromagnetic radiation by the selected character forming means so as to project a modified beam of radiation forming an outline corresponding to the selected character to be produced toward particles in the region of the selected portion of the recording area so that particles which are irradiated by the modified beam will absorb part of the radiation energy so as to change the properties of the irradiated particles, and producing only from the irradiated particles visible characters on the recording area while the relative position of the beam and the recording area is maintained.

The change in the properties of the radiated particles may be a color change, or a softening, respectively liquifying of the particles.

The apparatus according to the present invention mainly comprises support means movably supporting a sheet on which the characters are to be produced, a source of radiation spaced from the support means for producing a beam of electromagnetic radiation di-

rected toward particles located in the region of a face of the sheet opposite the face which is supported on the support means, and a plurality of character forming means for selectively influencing the beam of radiation produced by the source of radiation so as to project a modified beam of radiation forming an outline corresponding to the selected character forming means toward a selected portion of the sheet so that particles located in the path of the modified beam will be irradiated to thereby change the properties of the irradiated particles and to produce from such irradiated particles a visible character on the portion of the sheet while the relative position of the latter, the source of radiation and the character forming means is maintained.

The novel features which are considered as characteristic of the invention are set forth in particular in the appended claims. The improved device itself, however, both as to its construction and its mode of operation, together with additional features and advantages thereof, will be best understood upon perusal of the following detailed description of certain specific embodiments with reference to the accompanying drawing.

BRIEF DESCRIPTION OF THE DRAWING

FIG. 1 is a schematic view of an apparatus according to the present invention for influencing a beam of radiation produced by a source of radiation so as to project a modified beam of radiation forming an outline corresponding to a selected character toward a selected portion of a recording area;

FIG. 2 is a schematic partial view of a modified form of the apparatus shown in FIG. 1;

FIG. 3 is a schematic view of the major components of an apparatus according to the present invention in which the particles to be irradiated are located on the recording area;

FIG. 4 is a schematic view of a modified apparatus according to the present invention in which the particles to be irradiated are transported on a carrier past the recording area and transferred thereto by mechanical pressure;

FIG. 5 is a schematic view of a further modification which is similar to the embodiment shown in FIG. 4;

FIG. 6 is a partial view of an apparatus according to the present invention and illustrating application of particles to be irradiated onto the carrier;

FIG. 7 is a further partial view of an apparatus according to the present invention and showing a different method for applying particles to be irradiated to a carrier; and

FIG. 8 is a schematic view of a further apparatus according to the present invention for applying particles to be irradiated to a carrier and for transferring the irradiated particles from the carrier onto a recording area without applying mechanical pressure to the carrier.

DESCRIPTION OF THE PREFERRED EMBODIMENTS

The present invention relates to a method and apparatus for producing selected visible characters on successive portions of at least one recording area. The method is carried out by positioning a selected one of a plurality of character forming means adjacent a selected portion of the recording area to thereby influence a beam of electromagnetic radiation so as to

project a modified beam of radiation forming an outline corresponding to the selected character to be produced toward particles in the region of the selected portion of the recording area so that such particles will be irradiated by the modified beam and absorb part of the irradiated particles.

The character forming means are preferably in the form of a plurality of masks or portions of a single mask which are formed with cutouts or transparent portions corresponding to the shape of the selected character and such masks or mask portions are selectively placed between a source of radiation and the recording area so that only a modified beam of electromagnetic radiation having an outline according to the cutout or transparent portion formed in the selected mask or mask portion will pass toward the recording area.

The particles to be irradiated by this modified beam may be incorporated on the surface of the recording area, or the particles to be irradiated may be transported in a thin layer on a radiation permeable carrier strip which is moved spaced from and longitudinally along the recording area so that the irradiated particles in absorbing the radiation energy are softened and then transferred by pressure contact onto the recording area to which the softened particles will then adhere to form visible characters thereon, or the particles to be irradiated may be electrostatically charged and moved spaced from and longitudinally along the recording area for instance on a carrier band so that the particles which are irradiated by the modified beam will lose their charge and will be transferred on to the recording area by additional electromagnetic and/or electrostatic attracting force applied thereto.

Common to the three modifications according to the method of the present invention is a first step of modifying a beam of radiation emanating from the source of radiation so as to project a modified beam of radiation forming an outline corresponding to the selected character to be produced toward particles in the region of a selected portion of the recording area. As mentioned above, this is preferably accomplished by placing a selected one of a plurality of masks or selected portions of a single mask having cutouts or transparent portions according to the selected character to be produced therein in the path of a beam of radiation emanating from a source of radiation and directed toward the recording area. Various apparatus for placing such masks or mask portions in the path of a beam of radiation are known in the art, and FIG. 1 schematically illustrates such as apparatus.

As schematically shown in FIG. 1, this apparatus may comprise a plurality of pivotally mounted key operated levers A, A₁ and so on arranged side-by-side and each carrying a plurality of downwardly extending pins B arranged along the respective level spaced from each other according to the code different for each lever and adapted during depressing of the respective lever to close a plurality of switches C to produce in a coder in circuit with the switches coded impulses which are transmitted to a comparator D. A disc 2, which may be formed from thin sheet glass covered with an opaque layer of metal or the like, the opaque layer having in the region of the periphery a plurality of cutouts respectively of an outline corresponding to selected characters to be produced, for instance letters A, B, C and so on, uniformly spaced from each other and radially inwardly therefrom a plurality of uniformly spaced slots

E each corresponding to one of the cutouts, is rotated uniformly about a vertical axis by a motor. The disc 2 is further provided with a single additional slot F radially inwardly placed from the annulus of slots E and aligned with one of the same. Axially aligned with the annulus of slots E and the single slot F are two lamps G and H to one side of the disc so that the rays produced by the lamps G and H may pass during rotation of the disc 2 respectively through successive slots E and the slot F onto a pair of receivers J respectively axially aligned with the lamps G and H and located on the other side of the disc. The receivers J are connected to a counter K which in turn is connected to the comparator D and the latter is connected through a circuit L to a source of radiation 1.

The apparatus schematically illustrated in FIG. 1 will operate as follows: The counter K will start counting when during rotation of the disc 2 the single slot F will be in axial alignment with the lamp H so that the light beam emanating from this lamp will impinge on one of the receivers J. By depressing one of the levers impulses are transmitted to the comparator D corresponding to the number and spacing of the pins B on the respective lever and when these impulses correspond with the impulses counted by the counter K, the radiation source 1 will be momentarily energized while rotation of the disc may be momentarily stopped so that the beam of radiation 4 thus produced will pass through a selected cutout and thus produce a modified beam of radiation 4a according to the thus selected character toward the recording area 3. While FIG. 1 shows only two levers A and A1, it is to be understood that the apparatus has to include as many levers as are cutouts for characters to be printed on the disc 2.

FIG. 2 shows a slight modification of the arrangement schematically illustrated in FIG. 1 which may be used when the source of radiation 1, shown in FIG. 1 is continuously energized. In this modification the circuit L is not connected to the radiation source 1, but to an electromagnet M having a movable core to which a shutter N is connected for movement therewith in longitudinal direction. The shutter N has a dark opaque portion and a light transparent portion, and this shutter is biased by a spring 0 in the direction of the arrow I so that normally the opaque portion will be located in the path of the beam of radiation emanating from the source 1 and so that only if the magnet M is energized, the shutter N will be moved against the bias of the spring 0 to a position in which the transparent portion of the shutter is aligned with the rays 4 emanating from the source 1. As schematically indicated in FIG. 2 the shutter N is located closely adjacent the disc 2 between the light radiation source 1 and the disc. The shutter N may be formed from thin sheet metal and the transparent portion thereof may simply be a cut out formed in the sheet metal.

Similar apparatus as described above in connection with FIG. 1 and 2 for placing a selected portion of a disc carrying cutouts or transparent portions of an outline according to the characters to be produced into the path of rays emanating from a source of radiation are known in the art and a similar apparatus is for instance disclosed in the U.S. Pat. No. 2,787,654.

FIG. 3 schematically illustrates the use of a mask 2 and apparatus connected thereto, as described above in connection with FIGS. 1 and 2, in one embodiment according to the present invention. In this embodiment

the mask 2 is interposed between a radiation generator 1 and a record carrier 3 which carries on the face thereof facing the radiation generator 1 a layer of particles fixed thereto which are to be irradiated by the modified beam 4a.

In this embodiment the record carrier 3 is a radiation sensitive paper provided with a layer of particles fixed thereto which change their color when irradiated by the modified beam 4a. Such radiation sensitive papers are well known in the art and for instance described in the U.S. Pat. No. 3,028,254 to Edwin Allen Grant, Jr. When such papers are subjected to ultraviolet rays emanating from the radiation generator 1, the portions radiated by the modified beam 4a will change their color by absorbing the energy of the radiation. Papers with a particle layer sensitive to ultraviolet radiation will require a radiation intensity of 20 - 50 microwatt sec./cm² and the spectral region of the necessary rays is for ultraviolet sensitive papers in the region of 150 - 350 nanometer.

Other papers sensitive to heat rays are also described in the U.S. Pat. No. 2,953,454 which describes a paper provided with a layer composed of the following ingredients:

25

	Ingredients	Parts by Weight
	Carnauba wax	11
	Ourycury wax	4
	Lanolin	7
	Blown rapeseed oil	8
30	Mineral oil	11
	Crystal violet dyestuff	59

Such papers are to be irradiated with a radiation intensity of 50-150 milliwatt sec./cm² and the spectral region for such papers should be between 800 and 2,000 nanometer.

As radiation generators for the spectral region of 150- 350 nanometers discharge lamps or flash lamps are suitable whereas for the spectral region of 800 - 2,000 nanometer incandescent lamps or infrared lamps are best suitable.

Another embodiment according to the present invention is schematically illustrated in FIG. 4. The embodiment shown in this Figure comprises a radiation generator 1, a masking arrangement 2, which may be constructed as described above in connection with FIGS. 1 and 2, for inserting a selected one of a plurality of cutouts or transparent portions of an outline corresponding to the selected character to be printed into the path of the rays 4 emanating from the radiation generator so as to provide a modified beam of radiation 4a downstream of the mask. This modified beam 4a passes through the bottom wall of a pot-shaped hammer 7 which is transparent and for instance formed of glass, preferably of Plexiglass, and through formed of glass, preferably of Plexiglass, and through a likewise transparent carrier band 5 held in taught condition, by means not shown in the drawing, against the bottom face of the pot-shaped hammer 7. The carrier band 5 is formed from a flexible plastic material, for instant polyvinyl chloride. This material has not only to be transparent but also to withstand properly without softening the temperature it is subjected to during radiation. At higher radiation energies or temperature polytetrafluor-ethylene is preferably used instead of polyvinyl chloride. The bottom face of the carrier band

35

40

45

50

55

60

65

5 carries a thin opaque layer of thermoplastic material 5a which may consist of carbon black enclosed in wax. Such layer material is known in the art and it may for instance include 40 parts by weight of carnauba wax, 40 parts by weight of mineral oil and 15 parts by weight of carbon black.

Other materials usable for this purpose may be composed of 36 parts by weight of carnauba wax, 1 part by weight of ozokerit, 40 parts by weight of mineral oil, 5 parts by weight of oleic acid, 3 parts by weight of crystal violet, and 15 parts by weight of carbon black. This material will soften when radiated by the modified beam 4a and the softened parts of this layer 5a will then be transferred by pressure contact onto the recording surface 3 which in this case may be standard paper. A stationary stop 10 is provided abutting against the bottom face of the paper 3 and this stop may be formed from any suitable material, for instance, metal.

The pot-shaped hammer 7 carries fixed to the upper rim thereof in any suitable manner an iron ring 8 to which a flexible membrane 9, fixedly mounted at the outer periphery thereof on a stationary support, is connected to thus yieldably hold the ring 8 and the hammer 7 connected thereto in a rest position and centrally with respect to the radiation generator 1. A stationary magnet coil 6 is arranged coaxial with and downwardly spaced from the ring 8 so that the latter will be downwardly moved against the tension of the membrane 9 when the coil 6 is energized.

The above-described arrangement will operate as follows: After advance of the paper 3 into the position for printing a selected character thereon and simultaneously movement of the mask 2 to bring a selection generator 1, the generator 1 is energized so that a modified beam of radiation 4a will pass through the carrier band 5 whereby the layer 5a thereon will be locally heated according to the outline of the modified beam 4a, that is according to the outline of a selected character to be printed. The energy absorbed by the irradiated portion of the layer 5a will be sufficient to locally soften, respectively liquefy this layer.

An adjustable electronic time delay of known construction may be provided to energize the magnet coil 6 after the modified beam of radiation has acted for a predetermined time on the thermoplastic layer 5a to thereby draw the iron ring 8 against the bias of the membrane 9 into the coil 6 so as to momentarily press the carrier band 5 and the layer 5a on the bottom face thereof against the top face of the paper 3, which will transfer the locally softened portion of the layer 5a corresponding to the selected character onto the paper 3.

By the provision of proper means it can be assured that the transferred character will stick to and harden, respectively solidify on the paper 3 without causing the carrier band 5 to adhere to this paper. The above-mentioned materials for the carrier band 5 and for the layer 5a thereon will satisfy this requirement.

The necessary radiation intensity required for carrying out the method with the above-described embodiment is in the range of 20 - 100 milliwatt sec/cm² and the spectral region for the necessary radiation is in the region of 800 - 2000 nanometer. Incandescent lamps or infrared lamps are especially suitable as radiation generators in this case.

In order to reduce the surface tension of the carrier band 5 when the latter is formed from polyvinyl chlo-

ride it is preferred to apply to the bottom surface of the carrier band 5 a very thin layer of polytetrafluoroethylene, respectively to form the carrier band 5 from the last-mentioned material, Polytetrafluoroethylene has, as well known, a very small surface tension.

It is also possible to accelerate the return movement of the hammer 7 to its rest position as shown in FIG. 4 by providing an additional solenoid coil 11 upwardly spaced from the solenoid coil 6 which when energized will quickly lift the hammer 7 so that by the suction thus created on the bottom face of the hammer the carrier band 5 will be quickly lifted from the paper 3. For this purpose it may also be advantageous to provide at the bottom of the hammer 7 a rubber sleeve 12 which fluidtightly engages the upper surface of the carrier band 5. It is further advantageous to provide for energizing of the magnet coil 7 an exactly adjusted electronic control arrangement of known construction which will cause movement of the hammer 7 to its rest position at time in which the portion of the layer 5a transferred to the paper 3 is not fully hardened so that separation of the carrier band 5 and the paper 3 will occur before the hardening of the radiated layer portion 5a which is transferred onto the paper 3.

FIG. 5 illustrates schematically a further embodiment according to the present invention which will operate in a manner similar to the embodiment described above in connection with FIG. 4. In this embodiment the position of the hammer 13 and the stop 14 are reversed as compared to the arrangement shown in FIG. 4, that is the stop 14 is arranged to engage the top face of the carrier band 5, whereas the hammer 13 is arranged to engage the bottom face of the recording papers 3. In this case the stop 14 has evidently to be made of transparent material and it is preferably formed from Plexiglass. The arrangement shown in FIG. 5 has the advantage that the construction of the hammer 13 can be simplified. In addition it is possible to provide for the drive of the hammer for its working and return stroke an electrodynamic system 15 which will assure a maximum speed of the hammer movement.

The arrangement according to FIG. 4 and 5 has the advantage that a carrier band and the color layer 5a thereon may be used which during normal room temperature will not smudge and be color-fast.

Since the radiation energy necessary for softening respectively liquefying portions of the layer 5a will depend on the difference between the softening temperature t_s and the temperature t_o of the surrounding atmosphere, it is possible by preheating the carrier band 5 to a preheating temperature t_p before it is passed in the region of the radiation beam emanating from the generator 1 so that the amount of heat to be transmitted to the particles of the layer 5a by the beam 4a may be considerably reduced. For this purpose a heating element 16 may be provided adjacent the stop 14 in the region of the latter upstream of the path of the rays 4a, as considered in the direction of the movement of the carrier band 5 indicated by the arrow shown at the right portion of the band, and the heating energy transmitted from the heating element 16 to the stop 14 is preferably controlled by a thermostat 17 in circuit with the heating element 16 so that the preheating temperature of the stop 14 may be regulated in accordance with the temperature of the surrounding atmosphere.

Usually it is assumed that it is not necessary to produce carbon copies with the embodiments illustrated in FIGS. 4 and 5 since copies can be made in a simple manner with known copying processes. If, however, in special cases the described method should be used for the production of carbon copies, then it is possible to introduce between the hammer 7 respectively 13 and the stop 10, respectively 14 a plurality of carrier bands 5 with the layers 5a thereon and recording papers 3 alternately sandwiched therebetween in a plurality of layers so that for instance by selection of proper heat radiation a division on the plurality of layers will occur so that after energizing the radiation generator and movement of the hammer 4 respectively 13 along its working stroke a simultaneous printing of the desired character delineated by the beam of radiation 4a will occur in the various layers.

FIG. 6 schematically illustrates an arrangement to regenerate the layer 5a on the carrier band 5. For this purpose the carrier band 5 may be in the form of an endless band guided by guide rolls as shown in FIG. 6 about an endless path and movable in the direction as indicated by the arrow. After passing the printing position 51 schematically indicated in FIG. 6, the band 5 passes heatable calender rolls 52 which apply from a likewise heatable container 54 a new layer 5a of the composition as mentioned above to the band 5. Before entering the calender arrangement 52 the band 5 may be preheated by a heating device 55 which will assure that the layer 5a will be applied with uniform thickness to the band.

FIG. 7 schematically illustrates another arrangement for regenerating the layer 5a on the carrier band 5. This arrangement acts similar to the known xerographic principle. The endless carrier band 5 after passing through the printing position 51, schematically shown in FIG. 7, passes beneath an electric charging device 56 which for instance may apply a positive charge to the carrier band 5. The thus charge band passes above a radiation source 57 which due to the radiation will neutralize the charge imparted to the band at such position of the latter at which the printing layer has been removed in the printing position of the band. The band passes thereafter beneath a powdering chamber 58 in which likewise positively charged thermoplastic color powder is applied to the band which will stick to the latter only at a portion thereof in which no charge remains since at the other portions the positively charged band and the positively charged particles will repulse each other. This powdered band is then passed by a heating chamber 59 in which the newly applied powder is liquefied to form with the remaining portions of the layer 5a a uniform uninterrupted layer which is then passed again to the printing station 51. Color powders suitable for this process are for instance disclosed in the reissue U.S. Pat. No. 25,136 or in the U.S. Pat. No. 2,659,670.

FIG. 8 illustrates a further embodiment according to the present invention.

This embodiment includes also an endless carrier band 41, a portion of which is guided for movement in the direction as indicated by the arrow parallel to and adjacent to the recording surface 3 which in the case may also be standard writing paper. The moving band passes upstream of the beam of radiation emanating from the radiation generator 1, which is modified by passing through the mask 2, first through an electric

charging device 42 which charges the band in the manner as described above in connection with FIG. 7 and thereafter the band passes adjacent a spraying device 43 in which a thermoplastic powder of a composition as mentioned above in connection with FIG. 7 is uniformly applied against the outer surface of the band and due to the charge applied to the band the powder will adhere to the latter. When the thus prepared band passes into the printing position in which modified beam passes through the band 41 and onto the powder layer applied thereto, the electric charge applied to the band will collapse at the portion thereof impinged by the modified beam of radiation and at three portions the powder particles will move under the influence of an electric potential applied to the guide surface 44 or by an additional magnetic field onto the recording paper 3 to which it will stick due to the softening, respectively liquefying of the powder particles. The softening or liquefying can be realized by transferring an additional heating energy to the recording paper surface. This energy may be produced by conventional infrared radiation means or the like.

The radiation intensity for the first step should be in the order of 20-50 microwatt sec./cm² whereas for the second step irradiation energy in the order of 50-150 milliwatt sec./cm² is required. The spectral region for the first step should be in the order of 150-700 nanometer and for the second step 800-2000 nanometer. For the first step gas discharge lamps or incandescent lamps are best suitable and for the second step incandescent lamps or infrared lamps are best suitable.

As material for the band 41, the materials mentioned in connection with FIGS. 4 and 5 are suitable and a band material as described in the U.S. Pat. No. 3,392,642 may also be used in the embodiment as shown in FIG. 8.

The embodiment described in connection with FIG. 8 has some similarity with the xerox copying methods, for instance described in U.S. Pat. No. 2,735,785, 3,166,420, or 3,301,152.

The embodiment shown in FIG. 8 has the advantage that no hammer is provided so that the method carried out therewith is completely noiseless.

Instead of the radiation generators mentioned in connection with the various above-described embodiments, it is also possible to use a laser as radiation generator. Such lasers are advantageously used since they have very advantageous switching characteristics and produce a very high radiation energy. Radiation generators such as low pressure gas-discharge tubes, light emitting diodes, lasers and microwave, oscillators may be directly electrically controlled so that such radiation generators may be used in connection with the control arrangement shown in FIG. 1, whereas other radiation generators such as high pressure gas-discharge tubes, incandescent lamps or infrared lamps have to be used with an arrangement as described above in connection with FIG. 2 in which a shutter is used to control the beam of radiation.

It will be understood that each of the elements described above, or two or more together, may also find a useful application in other types of printing apparatus differing from the types described above.

While the invention has been illustrated and described as embodied in printing apparatus using a beam of radiation for producing selected characters on a recorded area, it is not intended to be limited to the de-

tails shown, since various modifications and structural changes may be made without departing in any way from the spirit of the present invention.

Without further analysis, the foregoing will so fully reveal the gist of the present invention that others can be applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed is new and desired to be protected by letters Patent is set forth in the appended claims.

1. A method of producing selected visible characters on successive portions of at least one recording area, comprising the steps of operating a selected one of a plurality of key means for positioning a selected one of a plurality of character forming masks adjacent a selected portion of the recording area; influencing a beam of thermal radiation by the selected character forming mask so as to project a modified beam of radiation having an outline corresponding to the selected character to be produced toward colored particles which soften when irradiated and which are connected to one face of a band facing said recording area; moving said band in a first direction substantially parallel to and spaced from said recording area through said modified beam so that the particles which are irradiated by said modified beam will soften; and moving a portion of said band on which said irradiated particles are located and an opposite portion of said recording area relative to each other in a second direction transverse to said first direction so that said irradiated softened particles will contact and adhere to a selected portion of said recording area to thus produce visible characters thereon.

2. A method as defined in claim 1, wherein said second moving step comprises the step of flexing said portion of said band toward said selected portion of said recording area.

3. A method as defined in claim 2, wherein said flexing of the band is carried out by imparting a sudden blow onto said portion of said band after particles thereon have been irradiated and softened by said irradiation.

4. A method as defined in claim 1, and including the step of preheating the band prior to the movement of said portion thereof over said selected portion of said recording area to preheat the particles on the band to a temperature below the softening point thereof.

5. Apparatus for producing selected visible characters on successive portions of at least one recording area comprising, in combination, support means movably supporting a sheet on which the characters are to be produced; a source of radiation spaced from said support means for producing a beam of electromagnetic radiation directed toward particles which change their properties when subjected to electromagnetic radiation and which are located in the region of the face of the sheet opposite the face which is supported on said support means; a plurality of character forming means for selectively influencing the beam of radiation produced by said source of radiation; means including a plurality of individually operable key means for placing a selected one of said plurality of character forming means into the path of said beam so as to produce a

modified beam of radiation forming an outline corresponding to the selected character forming means toward a selected portion of said sheet so that said particles located in the path of said modified beam will be irradiated to thereby change the properties of the irradiated particles and produce from said irradiated particles a selected visible character on a portion of said sheet, while the relative position of said sheet, said source of radiation, and said character forming means are maintained; means for transporting said particles in a layer of particles between said one face of said sheet and the respective character forming means which has been placed into the path of said beam, said transporting means comprising a band of radiation permeable material with a layer of particles applied to that surface of said band which faces said one face of said sheet; and means for transferring the irradiated particles from said band onto said one face of said sheet and comprising means for flexing a portion of said band located in the path of said beam of radiation toward said one face of said sheet so as to transfer the irradiated particles to the latter, said flexing means comprising a member of radiation permeable material arranged between said means for producing said beam of radiation and said band and movable from a rest to an active position deflecting said band, and means for moving said member suddenly from said rest to said active position.

6. Apparatus as defined in claim 5, wherein said particles are color particles which soften when irradiated.

7. Apparatus as defined in claim 5, wherein said member is cup-shaped member having an upper rim and a bottom wall facing the surface of said band opposite the surface of the latter to which said particles are applied, and including an annular component of magnetizable material fixed to said rim of said cup-shaped member, and wherein said means for moving said member comprises solenoid means cooperating with said component of magnetizable material.

8. Apparatus as defined in claim 7 and including biasing means connected to said member for yieldably maintaining the latter in said rest position.

9. Apparatus as defined in claim 8, wherein said biasing means comprises a flexible membrane connected at a central portion thereof to said member and fixedly mounted at the periphery thereof on a stationary support.

10. Apparatus as defined in claim 8 and including additional solenoid means cooperating with said magnetizable component for returning said member at accelerated speed to said rest position.

11. Apparatus as defined in claim 10, and including suction means fixed to the bottom end of said member and engaging said band.

12. Apparatus as defined in claim 4, wherein said particles are color particles which soften when irradiated, and including means outside the path of said beam of radiation for heating said additional support means to preheat the layer of particles on said band, prior to the radiation of said particles, to a temperature below the softening temperature.

13. Apparatus for producing selected visible characters on successive portions of at least one recording area comprising, in combination, support means movably supporting a sheet on which the characters are to be produced; a source of electromagnetic radiation spaced from said support means for producing a

beam of electromagnetic radiation toward particles which change their properties when subjected to thermal radiation and which are located adjacent a selected portion of one face of the sheet opposite the face which is supported on said support means; a plurality of character forming means for selectively influencing the beam of radiation produced by said source of electromagnetic radiation; means for transporting said particles in a layer of particles between said one face of said sheet and a selected one of said plurality of character forming means, said means for transporting said layer comprising an endless band movable in one direction; means outside the path of the beam of radiation for electrically charging said band; means for applying said particles in a layer onto the surface of said band which during movement of the latter faces said one face of

said sheet; and means including a plurality of individually operable key means for placing a selected one of said plurality of character forming means into the path of said beam of radiation so as to project a modified beam of radiation forming an outline corresponding to the selected character forming means toward said selected portion of said sheet so that said particles located in the path of said modified beam will be irradiated to thereby change the properties of the irradiated particles and to produce from said irradiated particles a selected visible character on a portion of said sheet, while the relative position of said sheet, said source of radiation and said character forming means are maintained.
